UNITED STATES PATENT OFFICE.

JAMES ARTHUR KIDWELL, OF DAYTON, OHIO.

DESIGN FOR A TRADING-CHECK.

45,559.

Specification for Design.

Patented Apr. 7, 1914.

Application filed June 9, 1913. Serial No. 772,701. Term of patent 14 years.

To all whom it may concern:

Be it known that I, JAMES ARTHUR KIDWELL, a citizen of the United States, residing at Dayton, in the county of Montgomery and State of Ohio, have invented a new, original, and ornamental Design for Trading-Checks, of which the following is a specification, reference being had to the accompanying drawing, forming a part thereof.

The figure is a plan view of a trading check showing my new design, which comprises a triangular figure upon which is superposed the word "Ingle" in a script

style of lettering with a flourish or streamer beneath the word "Ingle" upon which appears the word "System," the whole being inclosed in a circular outline.

I claim:—

The ornamental design for a trading check, as shown.

In testimony whereof, I have hereunto set my hand this 6th day of June, 1913.

J. ARTHUR KIDWELL.
